WORK-POSITIONING MEANS FOR BOX
BLANK MACHINES

Edward M. Florycyk, Rockaway, N. J., assignor to
Stapling Machines Co., a corporation of Delaware

Application January 21, 1936, Serial No. 60,027

3 Claims. (Cl. 198—131)

This invention relates to box-making machines and particularly to machines for making wirebound box blanks.

It is an object of the invention to provide improved means for positioning and conveying the box parts through the machine.

It is a further object of the invention to provide work-positioning and conveying means which are readily adjustable to accommodate box parts of different dimensions.

Other objects will be in part obvious and in part pointed out hereinafter.

In the drawings:—

Figure 1 is a vertical section of a wirebound box blank machine embodying the invention and showing the endless work-conveying means.

Fig. 2 is an enlarged front elevation, partly in section, seen from the line 2—2 of Fig. 1 with certain parts omitted for clearness of illustration.

Fig. 3 is an enlarged side elevation of one pair of driven sprocket wheels and the pair of work-conveying chains which are driven thereby.

Fig. 4 is an end elevation of the same with some of the links of the conveyor chains omitted for clearness of illustration.

Fig. 5 is an enlarged perspective view of a portion of a pair of work-conveying chains.

Fig. 6 is an enlarged side elevation of a portion of a pair of sprocket wheels and the pair of conveyor chains which are trained thereover.

Fig. 7 is a sectional view taken on the line 7—7 of Fig. 6.

Fig. 8 is a cross-sectional view of a pair of conveyor chains and the supports therefor and showing the manner in which the two chains are spaced laterally to receive between them and position a cleat or batten for a box blank.

Fig. 9 is a similar view but showing the pair of chains more widely separated to position a wider cleat or batten.

In the manufacture of wirebound box blanks, cleats and side sheets are positioned in proper relationship to each other on endless conveyor chains which carry the cleats and sheets beneath stapling mechanism which operates to drive staples into the sheets and cleats to secure them together and to staple binding wire thereto. A machine of this general type is disclosed in U. S. Patent to Thompson No. 1,738,806 of December 10, 1929.

As shown in said Thompson patent, each conveyor chain is channel-shaped to receive and position laterally the cleats for the box blank. Because of the fixed relationship of the side walls

of each conveyor chain, it will accommodate cleats of one width only, thus necessitating the substitution of a different chain for each different width of cleat to be operated upon.

The present invention is intended to provide a conveying means for cleats, the side walls of which may be adjusted laterally to accommodate cleats of different widths and thus eliminate the necessity of changing conveyor chains for cleats of different widths.

Referring to Fig. 2, the work-positioning and conveying means of this invention consists of two pairs of endless conveyor chains, the chains of one pair being designated 1 and 1^a respectively, and the chains of the other pair being designated 2 and 2^a respectively. The pair of chains are relatively adjustable laterally of the machine and the chains of each pair are also relatively adjustable laterally for a purpose herein-after explained.

As best shown in Figs. 5 and 6, each conveyor chain consists of a plurality of chain links pivotally connected by connecting links 3 to pass over sprocket wheels at either end of the machine. As shown in Fig. 1, each chain is driven by a driven sprocket wheel 4 keyed to a shaft 5 at the delivery end of the machine and passes over an idler sprocket wheel 6 rotatably mounted on a shaft 7 at the receiving end of the machine. Between the sprocket wheels 4 and 5 the chains are supported on guide supports 8, which are also laterally adjustable to accommodate lateral adjustment of the chains.

As best shown in Figs. 8 and 9, each support 8 is provided with a flange 9 which engages rollers 10 carried by the conveyor chain, and thus supports the chain through the rollers, thereby reducing frictional drag. The rollers 10 are so located as to permit the lower extremity of the side walls of each conveyor chain to extend below the top of the flange 9 of the support 8 and thus prevent lateral movement of the conveyor chain.

As best shown in Figs. 3 and 4, each sprocket wheel is provided with teeth 11 so spaced as to engage appropriate recesses formed in the connecting links 3, the recesses in the connecting links and the teeth 11 being so formed as to provide an arc of approach and recess such that the impact of contact between the chain and the sprocket wheel is small and a uniform speed of travel is imparted to the chains.

Each sprocket wheel is also provided between teeth 11 with a flange 12 adapted to extend into the recess formed by the side walls of each

conveyor chain link, as shown in Fig. 7, and thus prevents lateral movement of the conveyor chains as they pass over the sprocket wheels.

Referring to Fig. 5, a pair of conveyor chains 5 1 and 1^a is shown. The pair of chains 1 and 1^a are positioned relative to each other an appropriate distance to form a channel to receive a certain width cleat.

As best shown in Fig. 7, the outside chain 1 of 10 the pair of chains carries an upwardly extending inner flange 14 to position one side of a cleat or batten C, and to position one end of a sheet S. The inner side wall of the chain 1 is formed to provide a shoulder 15 upon which the cleat C 15 may rest. The links of chain 1^a are formed to provide a shoulder 15^a to support the other side of the cleat C, the two shoulders 15 and 15^a between them serving to support the cleat C.

The links of chain 1^a are also provided with 20 an upwardly extending flange 16 to position the other side of the cleat C. Thus, the flange 14 of the chain 1 and the flange 16 of the chain 1^a form a channel to receive the cleats C and to hold them against lateral movement.

25 For positioning the cleats endwise in the channel formed by the pair of chains 1 and 1^a and for propelling the cleats C with the chains, spacer or pusher blocks 17 are adjustably secured in a slot 18 formed in flange 16 of the chains 1^a. Each block 17 carries a laterally extending arm 19 to engage the rear end of each cleat C. The block 17 also carries an upwardly extending arm or fin 20 to engage the rear edge of each sheet S. The arms 19 and 20 may be formed integrally or separately and may be releasably secured to the block 17 to permit substitution of differently dimensioned arms 19 and 20 to accommodate different dimensioned box parts and the spacing thereof.

40 The links of chain 1 may be provided with slots 21 to which staple control blocks may be adjustably secured for controlling the operation of the stapling mechanism in the manner described in said Thompson patent.

45 Relative adjustment of chains 1 and 1^a to accommodate cleats of different widths is illustrated in Figs. 7, 8 and 9. In Fig. 7, a narrow cleat C is being operated upon and the chains 1 and 1^a are located close together to provide 50 a narrow channel to receive the cleat C. In Fig. 8, a wider cleat C is being operated upon and the chains 1 and 1^a are more widely separated. In Fig. 9 a wide batten or cleat C is being operated upon and the chains 1 and 1^a are more 55 widely separated than in Fig. 8.

55 To clinch the ends of any staples which may be driven through the cleats C, one or more clincher blocks 22 (depending upon the spacing between the chains) may be located between 60 chains 1 and 1^a. Many suitable types of clincher blocks and the operation thereof are well known and therefore will not be described herein, it being sufficient to say that such clincher blocks are located beneath the work and in vertical alignment with the staple driving mechanism 65 to receive the thrust of the staple driver and to clinch the ends of staples which may be driven through the work.

The use of two pairs of conveyor chains in-

stead of two single conveyor chains to position and feed sheets and cleats through the machine provides in effect two adjustable channels for 5 positioning box cleats which may be readily and quickly adjusted for cleats having different widths. This feature of my invention saves much time and labor in setting the machine for each new run of box blanks, as heretofore it was necessary to substitute a different chain for different width cleats.

10 The width of the cleat as referred to herein is the horizontal width of the cleat measured at right angles to its direction of travel. In the completed box this width is usually referred to as the depth of the cleat.

15 The width of the sheet as referred to herein is the width of the sheet measured at right angles to its direction of travel.

20 It will be noted that the conveyor chain links are supported primarily by rollers which contact the stationary guides for the chains. This arrangement greatly reduces frictional drag of the chains on their supporting guides and thus reduces wear and tear on the parts and contributes to a smoother operation and power saving.

25 It will be understood that the invention is not to be limited to the specific embodiment shown for illustration as the inventive features may be variously embodied without departing from the invention.

30 It will also be understood that all of the features of the invention need not be used conjointly, as they may be used in various combinations as defined in the subjoined claims.

I claim:

35 1. In a machine of the character described, means to position and feed cleats and sheets comprising a plurality of pairs of endless conveyors, each conveyor of each pair being provided with an arm and a shoulder to support and 40 position one side of a cleat whereby a cleat placed between the conveyors of a pair will be positioned vertically and horizontally, and the conveyors of each pair being relatively adjustable laterally to accommodate cleats of different 45 widths, and the pairs of conveyors being relatively adjustable laterally to accommodate sheets of different widths.

50 2. In a machine of the character described, means to position and feed sheets and cleats comprising a plurality of pairs of endless conveyors, each pair being constructed and arranged to support and position between them a cleat, and being relatively adjustable laterally to accommodate cleats of different widths, and the 55 pairs of conveyors being relatively adjustable laterally to accommodate sheets of different widths.

55 3. In a machine of the character described, means to position and feed cleats comprising a 60 plurality of pairs of endless conveyors, each conveyor of each pair being provided with an arm and a shoulder to support and position one side of a cleat whereby a cleat placed between the conveyors of a pair will be positioned vertically 65 and laterally, and the conveyors of each pair being relatively adjustable laterally to accommodate cleats of different widths.

EDWARD M. FLORCYK.
